UNITED STATES PATENT OFFICE.

SAMUEL M. CURWEN, OF PHILADELPHIA, PENNSYLVANIA, ASSIGNOR TO
JOHN A. BRILL, OF PHILADELPHIA, PENNSYLVANIA.

ARM-REST FOR SEMICONVERTIBLE OR OTHER CARS.

SPECIFICATION forming part of Letters Patent No. 739,799, dated September 22, 1903.

Application filed April 17, 1903. Serial No. 153,007. (No model.)

To all whom it may concern:

Be it known that I, SAMUEL M. CURWEN, a citizen of the United States, and a resident of the city and county of Philadelphia, State of Pennsylvania, have invented a new and useful Arm-Rest for Semiconvertible or other Cars, of which the following is a specification:

Semiconvertible cars—that is, that class of street or other cars in which the windows are adapted to be detached to convert the same into partly-open cars—are made with very wide windows and a low window-rail, so that the window-sash extends considerably near the seat. As the sash fasteners or locks are placed adjacent to the lower end of the sash and because of other considerations, it is not found practicable to place a guard-rail upon or adjacent the window-rail as a car-fixture to form an arm-rest for passengers, because such a rail would interfere with said fasteners and their operation and would involve a large expense in construction, fitting, and adding to the weight of the car unnecessarily.

The object of my invention is to combine an arm-rest that will not interfere with the sash-fasteners or their manipulation, be readily attachable or detachable, and which in itself involves certain novel details of construction. This object I accomplish by the means herein illustrated and described, which embodies the best known form of carrying out my invention, reference being had to the accompanying drawings, in which—

Figure 1 is an elevation of a portion of a semiconvertible car. Fig. 2 is a section taken on the line 2 2 of Fig. 1. Figs. 3, 4, and 5 are front, rear, and side elevations of one of the supporting-brackets. Fig. 6 is a plan view of the bracket. Fig. 7 is a section on the line 6 6 of Fig. 3, and Fig. 8 is a section on the line 8 8, Fig. 5.

Throughout the various views similar reference characters designate similar parts.

The construction of a convertible car to which I have applied my improvements contains the stanchions or posts 1, paneling 2, and window 3, which rests on the top rail 4 of the paneling 2 and against the sill 5, all of which form no part of my invention and may be suitably varied. The locks or sash-fasteners are usually located at the lower corners

of the sash 3, the bolts of which are substantially in line with the circle 3^a.

At 6 is an arm-rest, which stops short of the stanchions 1 a sufficient distance to be clear 55 of the fasteners or locks and is supported near each end by brackets 9. Each bracket comprises a flat and horizontal web 10, with perforations 11, through which screws pass to secure the bracket to the arm-rest. The 60 web 10 is made integral with converging webs 13 and 14 and inside web 14^a, web 13 being at the rear and longitudinally disposed, while the support 14 is at right angles and merges into the same at a point opposite to where it 65 is curved at 15 to fit and provided with holes 15^a for attachment to the sill 5, as shown in Figs. 1 and 2. This lower portion of the supporting-web is provided with holes 16, through which pass screws 17 to secure the brackets 70 to the said sill. For convenience only one arm, with its brackets, is disclosed, because it is obvious that as many are employed as there are panels in the car and that all are identical.

From the above it is evident that I have 75 described an arm-rest that in no way interferes with the sash or its fasteners and which may be readily attached or removed when the car is converted into "open" condition.

While I have shown and described one form 80 of bracket and arm, it is evident that these may be varied as to size, form, and number of brackets and proportion of parts without departing from the scope of my invention, so I do not consider myself limited to the embodiment of idea herein illustrated, but regard all structures as equivalents which come within the scope of the following claims.

Having thus described my invention, what I claim is—

1. In a semiconvertible car or similar vehicle, a panel, a bracket-support secured thereto, and an arm-rest secured to said bracket.

2. In a semiconvertible car or similar vehicle, a panel, a bracket-support secured thereto, and an arm-rest supported by said bracket-support, and so disposed as not to interfere with the sash-locks.

3. In a semiconvertible car or similar vehicle, a panel, an arm-rest connected with said panel, and disposed between stanchions of the car.

4. In a semiconvertible car or similar vehicle, an arm-rest secured to the panel adjacent to the window, fasteners on the window, said arm-rest being disposed within the longitudinal limits defined by said fasteners.
5. In a semiconvertible car or similar vehicle, an arm-rest supported on brackets fixed to the car so that the said arm-rest is disposed between the stanchions longitudinally ¹⁵ of the car.
6. In a semiconvertible car or similar vehicle, provided with stanchions, a top rail, and

window-sash, and an arm-rest fixed to said top rail by upwardly-extending brackets and which is located above the top rail in front ¹⁵ of the sash and between the stanchions.

Signed in the city and county of Philadelphia and State of Pennsylvania this 25th day of March, 1903.

SAML. M. CURWEN.
